UNITED STATES PATENT OFFICE

ARTHUR C. GAYNOR, OF STRATFORD, CONNECTICUT

DESIGN FOR AN ELECTRICAL FLUSH PLATE

Application filed October 26, 1928. Serial No. 28,651. Term of patent 14 years.

To all whom it may concern:

Be it known that I, ARTHUR C. GAYNOR, a citizen of the United States, residing at Stratford, in the county of Fairfield and State of Connecticut, have invented a new, original, and ornamental Design for an Electrical Flush Plate, of which the following is a specification, reference being had to the accompanying drawings, forming part thereof, in which

Figure 1 is a perspective view of an electrical flush plate, showing in dot-and-dash lines an opening for the passage of a switch lever.

Fig. 2 is an edge view to show the contour of the surface of the plate.

I claim:

The ornamental design for an electrical flush plate, as shown.

ARTHUR C. GAYNOR.
